UNITED STATES PATENT OFFICE.

WILLIAM MITCHEL FOLBERTH, OF CLEVELAND, OHIO.

APPARATUS FOR CLEANING AUTOMOBILE WIND-SHIELDS.

1,309,724.

Specification of Letters Patent.

Patented July 15, 1919.

Application filed April 7, 1919. Serial No. 288,414.

To all whom it may concern:

Be it known that I, WILLIAM M. FOLBERTH, a citizen of the United States, residing at Cleveland, in the county of Cuyahoga and State of Ohio, have invented certain new and useful Improvements in Apparatus for Cleaning Automobile Wind-Shields, of which the following is a specification.

My invention relates to apparatus adapted to clean windshields of automobiles, while not necessarily restricted to this use, as it may be used for various other purposes.

An important object of the invention is to provide apparatus of the above-mentioned character, having means to utilize the suction created in the intake manifold of the engine for causing the cleaning element to be automatically moved in contact with the glass or article to be cleaned.

20 A further object of the invention is to provide apparatus of the above-mentioned character having a diaphragm which is acted upon by the suction in the intake manifold of the engine, said suction being automatically controlled by valves shifted by the diaphragm.

25 A further object of the invention is to provide apparatus of the above-mentioned character, which is simple in construction, and reliable in operation.

Other objects and advantages of the invention will be apparent during the course of the following description.

In the accompanying drawings forming a part of this specification and in which like numerals are employed to designate like parts throughout the same:

Figure 1 is a perspective view of apparatus embodying my invention;

40 Fig. 2 is an enlarged central vertical longitudinal sectional view through the same, parts being shown in elevation;

Fig. 3 is a similar view through the apparatus, showing the diaphragm in the elevated position, shifting the valves to the opposite position;

Fig. 4 is a detail section, taken on the line 4—4 of Fig. 3; and

50 Fig. 5 is a central vertical longitudinal section through apparatus embodying a slightly different form of the invention.

In the drawings, wherein for the purpose of illustration is shown a preferred embodiment of my invention, the numeral 10 designates a diaphragm casing as a whole, com-

prising upper and lower sections 11 and 12, receiving a flexible diaphragm 13 therein, the casing sections and the diaphragm being secured together by bolts 14 or the like. The upper casing section 11 is preferably provided with ears 15, which are bolted or otherwise rigidly secured to the frame 10 of a windshield 16 having a section or glass 17 or the like, to be cleaned.

The lower casing section 12 is provided with a stuffing box 18, receiving a reciprocating rod 19, having a longitudinal opening 20 formed therein. The upper end of this rod is screw threaded and extends through an opening 21 formed in the diaphragm 13, and engages nuts 22 and 23. The nut 23 has its top closed, as shown, and is provided with a contracted opening 24 for a purpose to be described.

The lower portion of the reciprocating rod 19 is provided with rack teeth 25, engaging a pinion or gear 26, rigidly secured to a rod 27. This rod is journaled within a transverse horizontal sleeve 28, rigidly secured to a depending arm 29, rigidly secured to the lower casing section 10. To the forward end of the shaft 27 is secured the head 30 of the cleaner element, this head carrying a flexible blade 31, to contact with the pane of glass 17 to clean the same.

85 A valve casing 32 is formed upon the upper casing section 11, and embodies chambers 33, 34 and 35. The chambers 33 and 35 are adapted to have communication with each other through a port 36, the ends of which are provided with tapered valve seats 37 and 38. The chamber 34 is adapted for communication with the chambers 33 and 35 through the medium of openings 39 and 40, the walls of which are beveled to form valve seats. The chamber 34 has a port 41, which leads to the atmosphere.

100 Leading into the port 36 is a port 42, having communication with a pipe 43, which leads to the intake manifold of the engine. It is thus seen that suction or vacuum created in the manifold of the engine will be transmitted to the port 36. The chamber 33 has connection with a pipe 44, which leads into the casing section 12, beneath the diaphragm 13, as shown at 44.

105 The numeral 45 designates an upper tapered valve, operating above the valve seat 37 to engage and disengage therewith. This valve 45 is carried by a stem 46, of smaller 110

diameter than the chamber 36 and a lower valve 47 is secured to the stem 46, for movement therewith. The valve 47 is tapered and operates beneath the valve seat 38, to engage and disengage therewith. The numeral 48 designates a double acting valve, having upper and lower tapered faces to engage with the valve seats 39 and 40. The valve 48 carries a depending stem 49 pivoted to a horizontal bar 50, the opposite end of which is pivoted to the valve 47, as shown. The valve 48 and its stem are preferably of substantially the same weight as the valves 45 and 47 and their stem, so that the bar 50 is retained more or less horizontal. These valves are preferably constructed comparatively light. The bar 50 has pivotal connection with a link 51, as shown at 52, and this link 51 carries a head 52, operating within the opening 24, and adapted to contact with the nut 23, when the diaphragm 18 is moved to the end of its downward travel.

The operation of the apparatus is as follows:

When the valve (not shown) connected with the pipe 43 is open, the suction from the intake manifold of the engine is transmitted by the pipe 43 to the port 36. With the valves shifted to the position shown in Fig. 2, the suction is transmitted into the diaphragm casing above the diaphragm while the space beneath the diaphragm is in communication with the atmosphere through pipe 44, chamber 33, and port 41. The suction above the diaphragm causes the same to rise, and this upward movement continues until the nut 23 contacts with the bar 50, serving to elevate the same, and while valve 45 is unseated and valve 47 seated, the valve 48 then engaging the seat 39. The diaphragm casing above the diaphragm 18 is now placed in communication with the atmosphere, through the port 40 and port 41, while the pipe 43 is placed in communication with the lower portion of the diaphragm casing, beneath the diaphragm, such communication being established through ports 42, chamber 33, and pipe 44. It is obvious that the suction is now applied to the lower side of the diaphragm which descends. The valves remain in the upper position, as the suction is operating upon the valves 47 and 48, and this raised position is maintained until the ring 23 contacts with the head 52, the valves being again shifted to the lower position. The diaphragm 18 will then begin to rise as above explained.

In Fig. 5, I have shown a different form of apparatus, wherein the diaphragm is moved downwardly by means of a spring. This apparatus comprises a diaphragm casing 53 having a diaphragm 54 operating therein. A tubular rod 55 is connected with the diaphragm and extends to the exterior of the casing, within a guide 56. The upper

end of the rod 55 has a lower flange 57, and a cap-nut 58 has screw threaded engagement with the upper end and contacts with the diaphragm 55, clamping it to the flange 57. The rod 55 is provided with rack teeth 59, engaging a gear 60, rigidly secured to a transverse shaft 61, carrying a cleaning device 62, to contact with the glass of the windshield.

The upper portion of the diaphragm casing is equipped with ears 63 to be secured to the frame 64 of the windshield and a valve casing 65 is formed upon the diaphragm casing.

The numeral 66 designates a pipe, connected with the intake manifold of the engine to receive the vacuum or suction therefrom and this valve leads into a port 67 discharging into a chamber 68, having a tapered valve seat 69. The casing 65 is provided with a chamber 70 having a tapered valve seat 71.

The valve seat 71 is adapted to be engaged by a valve 72, which seats downwardly and is carried by a stem 73, carrying at its lower end an upwardly seating valve 74 to engage the valve seat 69. A rod 75 is connected with the valve 74 and carries a head 76, operating within the tubular rod 55, and adapted to engage with the nut 58.

A compressible coil spring 77 is arranged within the casing 53 and is held within a notch 78, and engages the cap nut 58, serving to move the diaphragm downwardly.

The operation of this form of apparatus is as follows:

When the valve (not shown) in the pipe 66 is open, suction is created within the casing 53, above the diaphragm, and the diaphragm rises. The valve 72 is now seated and the valve 74 unseated. The diaphragm continues to rise until the cap nut 58 contacts with the valve 74, whereby this valve is seated and the valve 72 unseated, thereby placing the casing above the diaphragm in communication with the atmosphere. The spring will now move the diaphragm downwardly, and when the end of the down stroke is reached the cap nut 58 will contact with the head 76 and again unseat the valve 74 and seat the valve 72. This operation will then be repeated.

It is to be understood that the forms of my invention herewith shown and described are to be taken as the preferred examples of the same, and that various changes in the shape, size, and arrangement of parts may be resorted to without departing from the spirit of my invention or the scope of the subjoined claims.

Having thus described my invention, I claim:

1. In apparatus for cleaning automobile windshields or the like, a diaphragm casing, a diaphragm arranged within the cas-

ing, cleaning apparatus connected with the diaphragm to be operated thereby, a pipe adapted for connection with a suction inducing means and adapted to have communication with the diaphragm casing upon one side of the diaphragm, a valve to control the communication between the pipe and the diaphragm casing, a valve for controlling the communication between the diaphragm 10 casing and the atmosphere, and means actuated by the movement of the diaphragm to shift the valves.

2. In apparatus for cleaning automobile windshields or the like, a diaphragm casing, a diaphragm arranged within the casing, cleaning apparatus connected with the diaphragm to be operated thereby, a pipe adapted for connection with a suction inducing means and adapted to have communication with the diaphragm casing, a valve for controlling such communication, a second valve for controlling the communication between the diaphragm casing and the atmosphere, a stem connecting the valves, and 25 means actuated by the diaphragm to shift the valves.

3. In apparatus for cleaning automobile windshields or the like, a diaphragm casing, a diaphragm arranged within the casing, a reciprocatory rack bar connected with the diaphragm and having a longitudinal opening, cleaning apparatus driven by the rack bar, a pipe adapted for connection with a suction inducing means, and adapted to 30 have communication with the diaphragm casing, means including a pair of valves to alternately place the pipe in communication with the ends of the diaphragm casing upon opposite sides of the diaphragm, means including a valve to place opposite ends of the 35 diaphragm casing upon opposite sides of the diaphragm in communication with the atmosphere, a transverse bar connected with the valves, a link connected with the bar and projecting into the opening of the rack bar, and an 40 45 projecting into the opening of the rack bar,

and a stop element carried by the end of the link and arranged within said opening.

4. In apparatus for cleaning automobile windshields or the like, a diaphragm casing, a diaphragm arranged within the casing, a reciprocatory rack bar connected with the diaphragm and having a longitudinal opening, a cleaning apparatus driven by the rack bar, a valve casting connected with the diaphragm casing upon one side of the diaphragm, said valve casting having an outer chamber, an inner chamber, a port connecting the outer and inner chambers and provided at its ends with valve seats, an intermediate chamber having openings leading into the outer and inner chambers which openings are provided with valve seats, the intermediate chamber having a port leading to the atmosphere, a pipe leading into the outer chamber and into the diaphragm casing upon the opposite side of the diaphragm, valves arranged to engage the valve seats of the port connecting the outer and inner chambers and having connection to move together, a valve arranged 60 within the intermediate chamber and adapted to engage the valve seats of the openings serving to connect the intermediate chamber with the outer and inner chambers, a transverse bar having connection with the valves, 65 a link connected with the bar and projecting into the opening of the rack bar, and an element carried by the end of the link.

5. In apparatus for cleaning automobile windshields or the like, a movable cleaner, a diaphragm casing, a diaphragm operating within the casing and connected with the cleaner to operate it, and means whereby the diaphragm is actuated.

In testimony whereof I affix my signature 85 in presence of two witnesses.

WILLIAM MITCHEL FOLBERTH.
